ATTORNEY

UNITED STATES PATENT OFFICE

SAMUEL H. ROBERTS, OF LEXINGTON, KENTUCKY

LUGGAGE CARRIER

Application filed September 6, 1929. Serial No. 390,771.

This invention relates to improvements in luggage carriers and it consists in the constructions, combinations and arrangements herein described and claimed.

An object of the invention is to provide a carrier by which the luggage which a motorist usually transports in making a trip can be conveniently and safely contained in a position generally on one of the running boards, thus leaving the interior of the vehicle unobstructed for the more comfortable riding of the passengers.

Another object of the invention is to provide a luggage carrier that is composed of heavy canvas or ducking, having the qualities of being water- and dust-proof as well as collapsible, so when not in use, it can be folded into a comparatively small compass and thus occupy little space either when carried in the vehicle or stored away.

Other objects and advantages will appear in the following specification, reference being had to the accompanying drawings, in which:—

Fig. 1 is a side elevation of the luggage carrier illustrating a typical installation on an automobile.

Fig. 2 is a cross-section of the luggage carrier taken on the line 2—2 of Fig. 1.

Fig. 3 is a detail sectional view taken on the line 3—3 of Fig. 1 and illustrating how portions of the luggage carrier are hooked over the edge of the running board.

Fig. 4 is a perspective view of the luggage carrier.

Every person who has ever undertaken an automobile trip of even a short distance has been confronted with the problem of disposing of the luggage, especially when it is intended to convey two or more persons in the vehicle. The common expedients are to load the interior, to the great discomfort of the occupants, or, in lieu of this, to strap the luggage on the running boards, rear tire carrier, or any other vantage point.

There are, of course, receptacles of various kinds on the market designed for the purpose of accommodating luggage, but usually these are hardly spacious enough and customarily comprise a part of the permanent equipment of the vehicle. The improved luggage carrier is devised with several purposes in view. It is constructed of heavy ducking or canvas, thus to safely contain whatever may be put into it. Being composed of a fabric, it follows that the carrier can be folded and compressed into a sufficiently small compass to warrant its being carried somewhere in the automobile. The carrier is equipped with enough guy ropes so that it can be securely tied to projections adjacent to one of the running boards. It also has facilities for limited adjustment so that varying quantities of luggage can be carried with equal facility.

Reference is made to the drawings. The luggage carrier, generally designated 1, is constructed of heavy canvas or ducking, as previously stated, which is either inherently waterproof or can readily be waterproofed, if desired. It consists of an elongated strip of material, the width of which represents the length of the luggage carrier. The length is variable, being proportioned to the various makes of cars on which the luggage carrier is designed to be used. The strip of material comprises a front 2, bottom 3, back 4 and cover flap 5.

Ends 6 are seamed to the front 2, bottom 3 and back 4 in such a manner as to leave an outstanding flange 7, clearly shown in Fig. 4. Here it is to be noted that the visible end 6 is co-extensive with the height of the front 2, the corresponding point 8 at the back 4 representing the place where the cover flap 5 hinges, as it were. Either grommets or metallic eyes 9 are affixed to the outstanding flange 7 at each end of the carrier, and through each set of the eyes a draw-string 10 is interlaced, as shown. The draw-string is 90

knotted at 11, not only preventing its pulling out of the eyes but affording a gripping place for the hand of the user. Certain ones of the grommets in the outstanding flanges remain unoccupied by the draw-strings. These grommets are denoted 11^a and 12. They are situated at the dividing places between the back 4 and cover flap 5, and the bottom 3 and back 4. Guy ropes 13 and 14, after being run through the grommets 11^a and 12, as well as leather or other loops 15 and 16 along the back 4 at places near the top and bottom of the carrier, are tied with knots 17 and 18. The remaining free ends of the guy ropes 15 are used to secure the inner bottom portion of the carrier to any convenient projection on the automobile.

Hooks 19 are suitably carried by those portions of the draw-strings 10 which appear on the outside of the flanges 7 near the front of the luggage carrier. These hooks are applied to the edge 20 of the running board, as indicated in Fig. 3. The hooks may be of any desired type, there being a number on the market suitable for the purpose. The hook shown in Fig. 3 is of a very simple style but in practice it may be held by a setscrew. Upon pulling up on the draw-strings 10, as in closing the carrier, the pull upon the hooks 19 will serve to assist in firmly anchoring the luggage carrier. The cover flap 5 is equipped with grommets or eyes 21 and 22. Cords 23, so tied through the eyes 21 at the free extremity of the cover flap as to leave a pair of ends, are intended to be secured to any convenient ones of the eyes 9 in the flanges 7. For example, should the carrier be rather lightly packed it would be possible to tie the cords 23 in one of the lowermost eyes 9. On the other hand, a heavily packed carrier would require the tying of the cords 23 in some of the uppermost eyes 9.

Similar cords 23 may be secure in the remaining eyes 21 of the cover flap 5 so that the medial parts of the side edges of the cover flap may also be tied down. The closure of the carrier is completed by a cord 24 secured, loosely or otherwise, in the eye 22. This eye is located in the approximate center of the front free edge of the cover flap. A ring 25 suitably secured to the front 2 near the bottom comprises a tying point for the cord.

The mode of use of the luggage carrier is readily understood. Although it is constructed to define the generally rectangular shape illustrated in Fig. 4, that shape is not necessarily preserved in the use of the luggage carrier. The luggage is packed in the carrier, whereupon the cover flap 5 is brought over and secured by means of its cord 24 to the ring 25. The closure is completed by tying the cords 23 in the most convenient ones of the eyes 9. The draw-strings 10 are then drawn tight, thus closing the end portions

of the carrier tightly around the ends of the luggage.

Before drawing the draw-strings tight the user may see to it that the hooks 19 are applied to the edge 20 of the running board. On the supposition that the guy ropes 13 and 14 were previously secured to projecting parts of the vehicle, the subsequent pulling upon the draw-strings will serve to engage the hooks with the edge 20 very tightly. It is not absolutely necessary to follow this specific procedure, because it is possible to completely enclose and compress the luggage and thereafter apply the hooks 19 to the edge 20 as well as to secure the various ends of the guy ropes 13 and 14 to the nearest projecting vehicle parts.

When the luggage carrier is not in use, it may be folded up in any convenient way. Being composed of fabric, it may be rolled or folded with only such regard as to direction as will reduce the carrier to the smallest possible compass. While the construction and arrangement of the improved luggage carrier is that of a generally preferred form, obviously modifications and changes may be made without departing from the spirit of the invention and the scope of the claims.

I claim:

1. A luggage carrier comprising a one-piece strip of material, and ends secured to corresponding marginal edges of the strip beginning at one end to define a pair of sides and a bottom, leaving the remaining end of one side free to extend over the top of the carrier and down along the remote side.

2. A luggage carrier comprising a strip of material, ends so secured to corresponding marginal edges of the strip beginning at one end of the strip as to produce outstanding flanges and leave a free portion of the strip to compose a cover flap, and draw-strings fitted in the flanges.

3. A luggage carrier having a front, bottom, back and cover flap, ends secured to the front, bottom and back to leave outstanding flanges, eyes fitted in said flanges, and draw-strings interlaced in the eyes.

4. A luggage carrier having a front, bottom, back and cover flap, ends secured to the front, bottom and back leaving outstanding flanges, eyes fitted in said flanges, draw-strings interlaced through certain ones of the eyes to enable drawing the ends of the carrier together, and guy ropes extending along the back adjacent to the bottom and the cover flap, being secured in the remaining eyes and having free ends for tying.

5. A luggage carrier having ends with adjoining flanges, said flanges being fitted with eyes, draw-strings interlaced in the eyes for constricting the ends of the carrier; a cover flap, and cords carried by the cover flap adapted to be threaded through convenient

ones of the eyes to secure the cover flap in a closed position.

6. A luggage carrier having ends and adjacent outstanding flanges, said flanges having openings, draw-strings interlaced through the openings to enable constricting the ends of the carrier, and means carried by an exposed portion of each of the draw-strings adapted to be applied to a portion of a vehicle to assist in holding the carrier in position.
